UNITED STATES PATENT OFFICE.

CHARLES GENTLE, OF HAMILTON, ONTARIO, CANADA, ASSIGNOR OF ONE-HALF TO ALEXANDER DONALD, OF HAMILTON, PROVINCE OF ONTARIO, CANADA.

AUTOMOBILE HEADLIGHT REFLECTOR.

Application filed March 20, 1924. Serial No. 700,638.

To all whom it may concern:

Be it known that I, CHARLES GENTLE, a subject of the King of Great Britain, and a resident of the city of Hamilton, in the county of Wentworth, in the Province of Ontario, Canada, have invented certain new and useful Improvements in Automobile Headlight Reflectors, of which the following is the specification.

My invention relates to improvements in automobile headlight reflectors and the object of the invention is to devise a reflector which will adequately illuminate the roadway without presenting any appreciable glare.

A further object is to devise a reflector in which the dazzling effect of the beam of light from the parabolic portion is reduced from a point immediately in front of the reflector by the projection of surrounding beams of diffused light thereonto.

A still further object is to devise a reflector which will give better illumination to the sides of the roadway and the ditches on each side thereof.

My invention consists of a reflector constructed and arranged all as hereinafter more particularly described and illustrated in the accompanying drawing in which:

Fig. 1 represents a front elevation of a reflector constructed according to my invention.

Fig. 2 is a section through the line 2—2 (Fig. 1).

Fig. 3 is a section through the line 3—3 (Fig. 1), and

Fig. 4 is a diagrammatic plan view illustrating the projection of the beam from the parabolic portion and the converging rays of light from the subsidiary reflecting portions.

Like characters of reference indicate corresponding parts in the different views.

1 is a reflector of general parabolic form. 2 is the electric bulb, the filament of which is positioned at the focus of the parabolic portion. 3 are a plurality of curved non-parabolic reflecting portions or cavities depressed from the parabolic surface of the reflector, the sectional form of the opposed non-parabolic reflecting portions being on a compound curve which cuts the central portion of the parabolic surface lying in advance of the same whereby a central parabolic surface 4 is constituted. The sides of

the portions 3 are curved inwardly toward the parabolic curve whereby a plurality of ribs 5 lying on such parabolic curve is constituted.

In the present embodiment of my invention the reflector is so formed that the ribs 5 are disposed at an angle of forty-five degrees to the vertical, although if so desired the ribs may be disposed horizontally and vertically. This is achieved by merely turning the reflector into the desired position.

The seat of the glare being the central parabolic surface portion 4 the amount of glare can be varied by varying the area of such portion 4. This is done by varying the curvature of the non-parabolic reflector portions 3 so that the curve of these portions intersects the parabolic curve further in advance or closer to the apex of the parabola. Obviously if the area of the portion 4 is increased there will be more concentrated light and more glare, and conversely, if such area is reduced there will be less concentrated light and less glare. The proportions illustrated give adequate illumination of the roadway and ditches while presenting no appreciable glare to a pedestrian or a person in a vehicle approaching from the opposite direction. In fact at no angle or distance in front of the reflector is the glare sufficiently dazzling to temporarily blind a person looking directly into such reflector.

The projected rays of the beam from the parabolic portion 4 are, of course, parallel while the projected rays of the independent beams from the portions 3 converge, such portions 3 being so formed that the beams converge on a point on the axis of the reflector immediately in front thereof. I find that about six inches in front of the reflector gives the best results.

The beams of light from the nonparabolic portions 3 being projected through the parallel beam from the parabolic portion 4 reduce materially the dazzling effect from such parallel beam.

In Figure 4 of the drawing *x* represents the parallel rays of light from the parabolic portion 4, *y* the converging rays from the portions 3 and *z* the continuation of the parabolic rays of the central beam distinguished so as to indicate that the dazzling effect is lessened.

Owing to the simplicity of construction my reflector can be readily manufactured by

stamping it out of a single sheet of metal. Thus the portions 3, the parabolic portion 4 and the ribs 5 are of integral construction. The cost of my reflector will, therefore, be 5 no more than an ordinary parabolic reflector, and in fact when it is considered that a plain glass can be used in front of it instead of an anti-glare lens the cost of the complete 10 headlight will be less than the present headlight.

From the above description it will be apparent that I have devised a simple and effective parabolic type of reflector in which the dazzling glare from the beam of concentrated light from the parabolic portion 15 is decreased to such an extent that it is negligible due to the projection of the surrounding beams of diffused light thereonto. Moreover, I have devised a reflector in which the 20 light therefrom will be evenly distributed across the width of the road.

What I claim as my invention is:

1. In a parabolic automobile headlight reflector, in combination a central parabolic reflecting portion, a plurality of non-parabolic reflecting portions depressed in the wall of the reflector and arranged around the parabolic portion, and ribs separating the non-parabolic portions and extending 30 from the vicinity of the forward edge of the reflector to the outer edge of the parabolic portion.

2. In a parabolic automobile headlight reflector, in combination a central parabolic reflecting portion, a plurality of non-parabolic reflecting portions depressed in the wall of the reflector and arranged around the parabolic portion, and ribs separating the non-parabolic portions and extending 40 from the vicinity of the forward edge of the reflector to the outer edge of the parabolic portion, the inner edge of each rib being on a continuation of the parabolic curve of the central parabolic portion.

45 3. In a parabolic automobile headlight re-

flector, the combination with a parabolic reflecting portion and a single source of light located at the focus of the parabolic portion, a plurality of opposed subsidiary curved non-parabolic reflecting portions depressed in the parabolic portion so as to leave an uninterrupted central parabolic portion, the central portion of the cross sectional curve of the opposed non-parabolic portions intersecting the curve of the parabolic portion, the sides of the non-parabolic portions curved inwardly to the parabolic curve whereby ribs are constituted between the non-parabolic portions, the edge of each rib being on the parabola. 55

4. In a light reflector, in combination a central parabolic reflecting portion, a plurality of nonparabolic reflecting sections formed in the wall of the reflector and separating mediums for said sections extending 65 radially from the central parabolic reflecting portion to the outer edge of the reflector.

5. In a parabolic automobile headlight reflector, in combination a central parabolic reflecting portion, a plurality of pairs of opposed non-parabolic reflecting portions depressed in the wall of the reflector, said non-parabolic reflecting portions arranged around the parabolic portion, ribs separating the non-parabolic portions, the opposed separating ribs being in the same plane. 70 75

6. In a parabolic automobile headlight reflector, in combination a central parabolic reflecting portion, a plurality of pairs of opposed non-parabolic reflecting portions depressed in the wall of the reflector, said non-parabolic reflecting portions arranged around the parabolic portions, ribs separating the non-parabolic portions, the opposed separating ribs being in the same plane, and the planes through the respective pairs of opposed ribs cutting each other at right angles. 80 85

CHARLES GENTLE.
